UNITED STATES PATENT OFFICE.

ALBERT BURGESS STAFFORD, OF CHICAGO, ILLINOIS.

COLLAR.

No. 848,575.

Specification of Letters Patent.

Patented March 26, 1907.

Application filed April 16, 1906. Serial No. 312,004.

To all whom it may concern:

Be it known that I, ALBERT BURGESS STAFFORD, a citizen of the United States, residing at Chicago, in the county of Cook and State of Illinois, have invented certain new and useful Improvements in Collars, of which the following is a specification.

This invention relates to improvements in shirt-collars, and more especially to the standing style, and has for its object to provide an article of this kind that will have a perfect fit and set and present a neat dressy appearance.

Under the ordinary arrangement it is difficult to have the ends of a collar meet or come together evenly on a line when worn. The present improvement brings the ends of the collar together evenly, so that the upper collar ends will not bend or stand in opposite directions.

In the drawings, Figure 1 is a view in perspective of a collar in its open position which embodies the improved features. Fig. 2 is a similar view showing the collar closed, and Fig. 3 is a detached view of the double flap or split end.

A represents a collar of the ordinary standing style, which may have the edges of the meeting ends straight up and down or made somewhat slanting, as taste or fashion may dictate.

The improvement presented herewith resides more especially in the buttoning-flaps or tab ends 4 and 5. The flap 4 is of the ordinary form and is provided with a button-hole 6. The flap 5 is made double or split inward from the lower corner end and presents the companion overlapping flaps 7 and 8 provided with buttonholes 9 and 10, as shown in Figs. 1 and 3. The line of the junction of the bottom edge of the collar and the split flaps runs diagonally, starting from a point above the buttonholes and running out or vanishing in the lower edge of the collar, as at 11.

Ordinarily the combined thickness of the companion button-flaps will approximately equal the thickness of the collar. When the ends of the collar are brought together in position to be buttoned, Fig. 2, the split flap 4 ends 7 and 8 straddle and overlap the flap 4 on each side and brings the ends of the collar together on a perfectly straight line, so that they stand evenly and present a neat dressy appearance.

When the flap ends are of the usual form and one buttons over the other, it is liable to have the effect of tipping or bending the upper corner ends of the collar in opposite directions or stand unevenly. By means of the present improvement these objections are obviated.

Having thus described my invention, what I claim is—

1. A collar having two projecting button-flaps integral with the body thereof, one of said flaps being split to receive the other flap between its divided parts and the three thicknesses of the flaps being correspondingly provided with buttonholes substantially as set forth.

2. A collar provided at one end with a double buttoning-flap integral with the body of said collar and adapted to receive the buttoning-flap on the other end of the collar between the two parts of said double flap substantially as set forth.

3. A collar provided at one end with a single projecting buttoning-flap only and on the other with a projecting double flap adapted to receive the former between its parts, these being the only parts of the article used in fastening the same substantially as set forth.

In testimony whereof I have signed my name to this specification in the presence of two subscribing witnesses.

ALBERT BURGESS STAFFORD.
